PUSHBUTTON CONTROL STATION

Neil J. Driscoll, 20980 Costanzo St.,
Woodland Hills, Calif. 91364

Continuation-in-part of design application Ser. No. 6,525,
Apr. 5, 1967. This application Sept. 5, 1967, Ser. No.
9,066

Term of patent 14 years

(Cl. D26—13)

Fig. 1.

Fig. 2.

Fig. 3.

Fig. 4.

FIG. 5.

FIG. 6.

FIG. 7.

FIG. 8.

FIGURE 1 is a front elevational view of the pushbutton control station;

FIG. 2 is a side elevational view of the design shown in FIG. 1;

FIG. 3 is a side elevational view, similar to FIG. 2, the annular button guarding element being shown in section;

FIG. 4 is a top plan view of the structure shown in FIG. 1;

FIG. 5 is a front elevational view of an alternate embodiment of the design;

FIG. 6 is a side elevational view of the design shown in FIG. 5;

FIG. 7 is a side elevational view, similar to FIG. 6, the annular button guarding element being shown in section; and

FIG. 8 is a top plan view of the structure shown in FIG. 5.

The dominant features of the design reside in the solid line portions.

This application is a continuation-in-part of my earlier application Ser. No. D.6,525, filed Apr. 5, 1967, for pushbutton control station.

The back of the design is generally planar and unornamented except for the four mounting discs as seen in certain side views.

I claim:

The ornamental design for a pushbutton control station, as shown and described.
